UNITED STATES PATENT OFFICE.

VICTOR H. KELLEY, OF MADISON, WISCONSIN.

DISPENSING MACHINE.

Application filed May 2, 1927. Serial No. 188,065.

This invention relates to dispensing machines, having reference more particularly to machines adapted to dispense matches whether packaged in rectangular boxes or in the well-known books.

One known type of dispensing machines for match boxes consists of an upright casing containing a vertical compartment with the articles piled up therein, a side delivery opening at the bottom of the compartment, and a laterally movable ejector which serves to push the lowermost article out of the delivery opening, at the same time supporting the superposed pile of articles in the compartment, and when retracted permitting the pile to drop onto the bottom or floor of the magazine preliminary to the next package-expelling movement of the ejector.

Some forms of these machines employ twin magazines located side by side with delivery openings in the opposite sides of the casing, and an ejector which alternately expels the lowermost article from the bottoms of the two magazines. Furthermore, machines of this type, when employed as vending machines, are usually further equipped with a coin-released locking mechanism controlling the movement of the ejector, and with a guard or guards for the delivery opening or openings serving to close the latter and prevent theft of the articles when the ejector is retracted.

Heretofore the side delivery opening at the bottom of the magazine has usually been rectangular in form, and of a size to permit the passage of either a single box of matches or of a pair of books of matches where the latter are stacked up in the magazine with the wide end of each book above the narrow end of the next underlying book, the books, as is well known, being of a general wedge shape longitudinally. So long as the books are piled in the magazine in the manner stated, a machine having a rectangular opening adapted to deliver a single box of matches will serve equally well to deliver a pair of books of matches. But it frequently happens that the person loading the magazine fails to observe the alternating order of piling up the books. That is to say, two or more adjacent books are frequently displaced in the magazine with their wide ends

superposed on each other. When such a pair of books reaches the bottom of the magazine, the two wide ends of the books are too high to go through the delivery opening, and the machine jams.

The object of my present invention is to provide a simple, practical and inexpensive construction of delivery opening and ejector, whereby a pair of books will be expelled from the bottom of the magazine through the delivery opening, and without any jamming of the machine, entirely irrespective of the manner in which the books may be arranged in the pile.

Since my present invention deals simply with the novel forms of the delivery opening and the ejector whereby the above-stated object is accomplished, I have not, in the drawings accompanying this application, attempted to show other details of the machine, such as the ejector locking and actuating mechanism, and the opening guards, for which any desired or approved devices may be used.

Referring to the drawings,—

Fig. 1 is a side elevation of the lower portion of a dispensing machine showing the delivery opening and the ejector, and the superposed match books, the lowermost two of which are disposed with their wide ends rearward and superposed;

Fig. 2 is a similar view, wherein the lowermost two books are disposed with their wide ends forward and superposed;

Fig. 3 is a similar view, wherein the lowermost two books are shown with their wide and narrow ends relatively superposed, so that the combined structure is substantially rectangular;

Fig. 4 is a perspective detail of the ejector.

Referring to the drawing, the housing of the machine comprises in general a cast-metal base 10 mounted on feet 11, and a superposed rectangular sheet-metal casing 12. In practice this latter is commonly divided by a transverse partition 13 into front and rear compartments, and the front compartment is divided by a partition 14 into twin vertical magazines. In each side of the housing at the bottom of each compartment is formed a delivery opening designated as an entirety by 15. As herein

shown the bottom and side edges of the opening are formed in the base 10, while the upper edge of the opening is constituted by a portion of the lower edge of the side wall 12; but so far as the present invention is concerned it is immaterial in what part of the structure the opening is formed. In the base 10 is a bottom plate 16 for the magazines, on which the lowermost article of the stack comes to rest when the ejector, hereinafter described, is withdrawn laterally from beneath the magazine. The lower edge of the opening 15 is substantially flush with the bottom plate 16.

15 The lower edge 17 of that portion of the casing side wall 12 which forms the upper edge of the delivery opening 15 is given the shape of a widened V, the purpose of which will hereinafter appear. Reciprocable side-
20 wise over the bottom plate 16 is the ejector 18 shown in isolated perspective view in Fig. 4. This comprises preferably a channel-shaped member having parallel vertical side walls and a top wall 19 that takes the shape
25 of a widened inverted V. The inclined sides of the top edge 17 of the delivery opening preferably form substantially the same angle to the horizontal as do the inclined sides of the top wall 19 of the ejector. In the structure herein shown the rear end of the ejector is mounted on the lower end of a pendulum bar 20 which extends rearwardly beneath the partition wall 13 and at its upper end is pivotally suspended from a point near the top of
30 the wall 13, as fully shown in a prior application filed by me April 2, 1927, Serial No. 180,408. In practice, also, the openings are equipped with suitable guards and guard-actuating devices, the structural details of which have no reference to the present invention, but preferably those shown and claimed in my aforesaid application are employed.

15 To illustrate the manner in which the described construction serves to always deliver the lowermost pair of match books without any clogging or jamming of the machine, in Fig. 1 I have shown the lowermost pair of match books B and B' at rest on the bottom plate 16 opposite the delivery opening 15 with their wide ends rearward and superposed, the two books thus producing a substantially triangular or wedge-shaped object. When the ejector is swung to expel the books, it acts upon the inner or rear edges of both books, and the rear or inner edge of the opening is high enough to permit the books to pass. At the same time the lower central portion of the V-shaped upper edge 50 of the opening holds back the next superposed book.

Fig. 2 shows the books B and B' arranged relatively the same as in Fig. 1 but with their superposed wide ends foremost. Since 55 the opening 15 is symmetrical at its two

ends the apexes of the opening edge and the ejector being mid-width of the opening, the two lowermost books can pass freely through the opening under the thrust of the ejector, the same as described in connection with Fig. 1, the V-shaped lower portion 17 of the side wall acting to hold back the next superposed book.

In Fig. 3 the lowermost pair of books B and B' are disposed relatively as they should be normally, that is with the wide end of one book registering vertically with the narrow end of the other, the two books thus producing a substantially rectangular object. The height of this object is slightly less than the height of the apex of the V-shaped upper edge 17 of the opening above the floor 16. Hence, when the ejector is shifted sidewise to expel the lowermost two books, the latter will pass freely through the opening.

The purpose of giving the described double slope to the top edge of the ejector 18 will be apparent from an inspection of Figs. 1 and 2. In the arrangement shown in Fig. 1, the forward slope of the top edge of the ejector 18 prevents the latter from striking the wide end of the third book from the bottom which is held back by the top edge portion of the opening. In the arrangement shown in Fig. 2 the rearward slope of the top edge of the ejector manifestly performs the same function.

From the foregoing it will be seen that the described construction of ejector and delivery opening enables the machine to invariably deliver a pair of books, and no more, without any jamming of the machine, irrespective of how the books are piled up in the magazine.

105 I claim:—

1. In a dispensing machine, the combination of a housing having a bottom plate and a magazine for articles to be dispensed and formed with a delivery opening opposite the lower end of said magazine, the upper edge of said opening being of a wide V-shape, and an ejector movable over said bottom plate to push articles through said opening, the upper edge of the working face of said ejector being of a wide inverted V-shape.

2. In a dispensing machine, the combination of a housing having a bottom plate and a magazine for articles to be dispensed and formed with a delivery opening opposite the lower end of said magazine, the lower edge of said opening being substantially flush with said bottom plate and its upper edge being of a wide inverted V-shape, and an ejector movable over said bottom plate to push articles through said opening, the lower edge of the working face of said ejector being substantially parallel with the lower edge of said opening and its upper edge being of a wide inverted V-shape.

3. In a dispensing machine, the combination of a housing having a bottom plate and a magazine for articles to be dispensed and formed with a delivery opening opposite the lower end of said magazine, the upper edge of said opening being of a wide V-shape, and an ejector movable over, said

bottom plate to push articles through said opening, the upper edge of the working face of said ejector being of a wide inverted 10 V-shape; the apexes of said opening edge and said ejector face lying midway of the width of said opening.

VICTOR H. KELLEY.
